UNITED STATES PATENT OFFICE.

ALBERT D. MACPHERSON, OF CHICAGO, ILLINOIS.

ELECTRIC HEATING APPARATUS.

1,321,221.

Specification of Letters Patent. Patented Nov. 11, 1919.

Application filed May 27, 1918. Serial No. 238,806.

To all whom it may concern:

Be it known that I, ALBERT D. MACPHERSON, of the city of Chicago, in the county of Cook and State of Illinois, and temporarily residing at 148 Vendome avenue, Notre Dame de Grace, in the city of Montreal, county of Hochelaga, and Dominion of Canada (whose post-office address is 148 Vendome avenue, N. D. G., Montreal, Canada,) have invented certain new and useful Improvements in Electric Heating Apparatus; and I do hereby declare that the following is a full, clear, and exact description thereof.

15 My invention relates particularly to a device the essential of which may be applied to either the heating of water or a plate surface, the latter to be used as a hot-plate or with slight modification a sad-iron. The 20 invention may be said broadly to consist of a core having as a component part an auxiliary element, a primary winding and a heat transmitting member integrally united to the core and forming a magnetic portion 25 thereof such member being of a section to carry the flux in the rest of the core, and a heat producing annular member in intimate relation with the said heat transmitting member and serving as a secondary winding.

As just mentioned, my invention is capable of several applications and for purpose of illustration, I will describe it specifically applied to a heater for flowing water and 35 a heater for a flat surface such as the well known hot-plate. The water heater, according to my invention, comprises a core, in the form of a relatively heavy iron pipe for conducting the water to be heated, this 40 pipe being surrounded and having in intimate contact therewith an annular or short circuited strip of metal serving as a secondary winding, while the primary winding encircles the secondary and is insulated 45 therefrom by any suitable insulation pressed on the pipe and inclosing the secondary. The core and its auxiliary element are preferably laminated. In the case of the flat surface, the hot plate for instance, the heat 50 transmitting leg of the core consists of a magnetic member which is an integral part of the hot-plate and of such section as to carry the flux in the rest of the core, the annular metal secondary being also an integral part of the hot-plate.

For full comprehension, however, of my invention, reference must be had to the accompanying drawings in which similar reference characters indicate the same parts, and wherein;

60 Figure 1 is a longitudinal vertical sectional view of a water heater constructed according to my invention;

Fig. 2 is a transverse sectional view thereof taken on line 2—2 Fig. 1;

Fig. 3 is a detail view of a water heating system having my invention applied thereto;

Fig. 4 is a side elevation of an electrical hot-plate containing my invention;

Fig. 5 is an end elevation thereof; and

Fig. 6 is a detail perspective view of the hot-plate and the parts formed integrally therewith removed.

The essentials of my invention are illustrated in the various figures of the drawings in their peculiar embodiments to suit the particular applications. In Figs. 1, 2 and 3, illustrating the heater for flowing water, the magnetic core consists of a pipe 10 having as a component part an auxiliary 75 laminated element 12 of U-form, the legs of the U,—14 and 15 being furnished at their ends with lugs 16 by which they are magnetically united to the ends of the pipe 10 which is sufficiently heavy between the 80 legs 14 and 15 to carry the flux. The lugs 16 are preferably formed with tapped holes and screwed upon the ends of the core 10, the lugs being secured to the ends of the legs by screw bolts 11. This core is surrounded 85 by a secondary winding which consists of a sleeve 18 preferably formed by a strip of metal of slightly less width than the space between the lugs 16 thus leaving a clearance 90 between the secondary and these lugs, such strip being wrapped around the core with the ends abutting and welded, or otherwise short-circuited. A suitable insulation indicated at 20 is pressed on the core in these 95 clearance spaces and completely over the 100 secondary thereby completely insulating the same; while the primary winding, preferably a coil 21, surrounds this insulation and the secondary. When this primary is energized a magnetic flux is induced in the 105 core and its auxiliary element and this flux in turn induces a current in the secondary 18. This current produces the heat which when transmitted through the core 10 to the 110 water flowing therethrough, will heat the

latter, and the heat transmitted through the pipe may be readily varied by increasing or decreasing the number of turns in the primary coil.

5 In Figs. 4, 5 and 6, in place of the pipe as a heat transmitting leg of the core, a rib 30 is employed. This rib is of magnetic metal and of such section to carry the flux in the rest of the core, and is cast integrally 10 with the hot-plate, indicated at 31, and extends diametrically across one side thereof. The secondary in this embodiment is extension 32 of the hot plate and is also cast integrally therewith and is of annular form 15 surrounding the primary coil 33 which is carried by the laminated core 34. The auxiliary element of the core which is also laminated is indicated at 35 and with its legs in intimate magnetic connection with the 20 rib 30 and the adjacent side of the hot-plate. Screws 60 rigidly secure the auxiliary element to the core. When the primary 33 is energized a magnetic flux is induced in the core and this flux in turn induces 25 a current in the secondary 32. This current produces the heat which when transmitted directly and through the rib 30 to the plate 31 heats the same. As in the embodiment for heating flowing water the temperature of the plate may be varied by increasing or decreasing the number of turns 30 in the primary coil.

The variation of degree of heat produced, to meet varying conditions or requirements, 35 is effected by a switch indicated at 50.

What I claim is as follows:—

1. An electric heating device comprising a primary winding, a core, a laminated auxiliary element of substantially U-form each 40 lamination being flat and of uniform width and thickness throughout, means rigidly securing the laminations together, and a secondary winding insulated from the core

consisting of an annular heat producing member surrounding the core. 45

2. An electric hot-plate comprising a plate, a core, a laminated auxiliary element of substantially U-form formed integrally with the core, the plate having an integral middle rib of such section to carry the flux 50 in the core, and a secondary winding consisting of a heat producing ring of greater depth than thickness and forming an integral extension of the plate and rib; and a primary winding carried by the core. 55

3. An electric hot-plate comprising a plate, a core, a laminated auxiliary element of substantially U-form formed integrally with the core, the plate having an integral middle rib of such section to carry the flux 60 in the core and a secondary winding consisting of a heat producing ring of greater depth than thickness and forming an integral extension of the plate and rib; a primary winding carried by the core; and 65 means for regulating the heat produced.

4. An electric hot-plate comprising a plate having a transverse middle rib upon its underside of magnetic metal, a secondary winding consisting of a heat producing ring 70 of greater depth than thickness forming an integral extension of the plate and ring, a core located centrally of the ring, a primary winding upon the core and a laminated auxiliary element of substantially U- 75 form straddling the ring and formed integrally with the core, the core and element being spaced from the secondary for the purpose of reducing magnetic leakage.

In testimony whereof I have signed my name to this specification in the presence of two witnesses.

ALBERT D. MACPHERSON.
